UNITED STATES PATENT OFFICE.

JOSEPH T. SIMPSON, OF CHICAGO, ILLINOIS.

SCREENING AND SEPARATING MACHINE.

Application filed December 10, 1923. Serial No. 679,539.

To all whom it may concern:

Be it known that I, JOSEPH T. SIMPSON, a citizen of the United States of America, and a resident of Chicago, county of Cook, and State of Illinois, have invented certain new and useful Improvements in Screening and Separating Machines, of which the following is a specification.

My invention relates to screening and separating machines, and has for its object improvements in devices of that character. More particularly the object is to provide a superior device for cleaning and reclaiming sand once used in making castings so that the cleaned sand may be used over again for additional casting purposes.

In foundry practice it is desirable to have the sand of large grains and free from foreign material when used to make molds for castings. In making molds, the ramming of the sand crushes some parts to dust, and in the making of castings, the heat of the metal disintegrates the sand with which it come in contact, and the consequent dust permeates the body of the remaining sand. In the mixing process of preparing sand for use in molds, the sand grains are coated with clay or other bonding material. In the casting process, this bonding material is destroyed for bonding purposes by the heat of the hot metal, but adheres to the grains of sand. One of the main objects of the present invention is to free the grains of sand from this destroyed bonding material so that the clean sand grains may be again coated with new bonding material and be used again in the making of other castings. Also, when castings are removed from the mold, much of the sand is in lumps. Another of the main objects of the present machine is to break up these lumps, and to separate the large grains of sand from dust and tailings.

In the accompanying drawings—

Fig. 1 is an elevation;

Fig. 2 is a central section partly in elevation, at right angles to Fig. 1; and

Figs. 3 and 4 are sections on lines 3—3 and 4—4, respectively, of Fig. 2.

Standing on the floor or other base 10 are two standards 11 and 12 which support the entire apparatus. At their upper ends these standards are secured to a beam 13, or other part of the building within which the machine is located. Connected to these stand-

ards are cross beams 14 and 15 which carry bearings 16 and 17 for the drive shaft 18. This shaft is driven in a clockwise direction as seen in Figs. 3 and 4.

Secured to the standards 11 and 12 by brackets 24 is ring 25, and secured to this ring by brackets 19 and suitable bolts is a metal ring 20, the lower edge of which inclines inward in a conical direction as shown at 21 in Fig. 2. Secured to this inclined part is a conical screen 22, the lower end of which terminates in a spout 23. Secured to the lower edge of ring 25 is a sheet metal cone 26 which surrounds the screen 22 at some distance therefrom. The lower end of cone 26 terminates in a spout 27, and the spout 23 extends thru the wall of the cone 26 as shown in Fig. 1.

On the lower end of the shaft 18 is a head 28, and on this head are fan blades 29. The upper parts of these blades are located within the ring 20, and the lower parts are in the cone 22. The shape of the outer edges of the blades corresponds in general with the shape of the ring 20, and are of about the size and shape indicated in Fig. 2. Between the blades 29 and secured thereto by angle irons 30, are plates 31 set in an inclined direction so that taken together they form a cone thru which the blades 29 project.

The upper end of the ring 25 is closed by a cover 32 which has a central opening and over this opening is a hopper 33. The cover 32 and hopper 33 are in two parts secured together by flanges 34 and bolts 35. A pipe 36 having a branch 37 is connected thru two points in the cover with the interior of the ring 25 and outside of the ring 20. The outer end of pipe 36 is connected in the ordinary way to an exhaust fan.

Inside of the cone 26 and over the spout 23 is a piece of sheet metal 38 which serves only to keep material from piling up on top of spout 23.

In operation a belt connected to pulley 39 drives the shaft 18 and fan 29 at high speed. With the exhaust fan in operation, air flows inward thru the hopper 33, the fan 29 and screen 22 to the space around the screen. From here it flows upward thru the annular space between rings 20 and 25 and thence thru pipe 36 to the discharge of the exhaust fan.

While this is in operation, used material

from the foundry is shoveled into the hopper 33 and falls on the fan 29. Lumps of sand thus falling on the fan are hurled outward with great force against the inner face of the ring 20, and then fall downward. The ring 20 is in fact a breaker ring. The material first reaches the fan at near its central portion, and as it moves outward under the action of the blades, its velocity increases until it is thrown against the ring with a velocity equal to that of the outer edges of the blades. In this operation, the plates 31 prevent material from falling from the hopper thru the fan without being hurled against the breaker ring 20. At the same time the plates 31 leave the lower conical part of the fan free to operate over the adjacent screen surface.

From the breaker ring 20 the material moves downward to and over the screen 22. That part of the material which is fine enough to pass thru the screen falls into the cone 26, while the tailings pass outward thru the spout 23. Accompanying this flow of material thru the screen is a flow of air which also enters thru the hopper. It is to be observed that the diameter of the fan 29 is greater than the diameter at the bottom of the hopper 33, and as a consequence there will be such a flow of air thru the hopper and the screen, even when there is no exhaust applied to pipe 36. The intention is, however, to have exhaust applied to pipe 36 for the purpose of removing dust from the sand and conveying it away. In this process the air flows thru the screen and then turns upward, carrying the dust with it. The heavier particles of sand fall down-

ward and pass thru the spout 27 to any convenient receptacle.

When air is forced thru the screen as above described, it loosens the sand up, or "aerates" it as the term is used in foundry practice. This is a desirable result which is produced by this construction.

What I claim is:

1. In a machine of the class described, a fan and means for driving it, a fan chamber having its lower portion consisting of a conical screen, a conical casing surrounding the fan chamber and removed a short distance therefrom, discharge spouts for the chamber and the casing at the apexes thereof, and an exhaust pipe connected to the upper part of the annular space between chamber and casing.

2. In a machine of the class described, a breaker ring, a conical screen connected to the lower edge of the ring and terminating in a central spout, a cover for the ring and provided with a central opening, a fan located in the ring and screen and having the outer edges of its blades corresponding to the shapes of the ring and screen, and inclined partition plates located between the blades of the fan.

3. In a machine of the class described, a chamber having its lower portion consisting of a conical screen, a fan located in the chamber and having the lower portion of its blades tapered to correspond to the conical form of the screen, and partitions between the blades and intermediate between the upper and lower portions thereof.

JOSEPH T. SIMPSON.
